Attorney.

UNITED STATES PATENT OFFICE

FREDERICK H. HUMMEL, OF BROOKLYN, NEW YORK

TOP-LIFT-TRIMMING MACHINE

Application filed August 6, 1929. Serial No. 383,823.

This invention relates to machines for trimming the edges of the top lifts of shoes and particularly to those heels which have curved breasts. It matters not whether the said top lift is of leather, fibre, paper or other material.

The invention is for the specific object of speeding up the work in finishing the heel, whether it be with a plain or beaded edge. While those heels so finished belong to ladies' and misses' shoes, yet the bead may be to advantage placed on any heel finished by the device herein described.

An object of the invention is to speed up production, on any class of heels, irrespective of their design, be it for a broad heel, a Cuban heel, or what is general, the high heel having attached thereto a lift placed on its end, and which the herein described device is adapted to trim to the exact shape of the heel.

Another object of the invention is to provide a device that leaves to the operator only the operation of setting up the device for the particular heel, and yet adapted to trim any and all top lifts as desired, without any hand operation on the same.

A more particular object is to provide a mechanism that is adapted to be adjusted from the front of the machine, each and every adjustment adapted to give the desired finish to the top lift of the heel. The simplicity and accuracy and quickness of these adjustments all tend to saving of time and consequently to the advantage of the production.

The invention will be better understood from the following description taken in connection with the accompanying drawing, wherein is shown what is now considered the preferred form. While the drawing illustrates merely some examples of means for putting my invention into practice, its scope will be pointed out in the specification and in the appended claims.

Further objects and advantages will become apparent as the description of the invention is hereinafter developed.

In the drawing, Fig. 1, is a front view of the upper part of a top lift heel trimming machine, showing in face view my improvement applied thereto; Fig. 2 is an enlarged detail

view of the trimmer head, the trimmer and associated parts in position; Fig. 3 is a detached detail showing the trimmer guard for turning the article and concave breasts of heels; Fig. 4 shows a face view of a modified form of guard; Fig. 5, a top plan view of the platform, operating parts being omitted; Fig. 6 is a detached vertical section of the guard; Fig. 7 shows another modification of the guard, and Fig. 8 is the lower part of a heel showing the top lift applied as it is introduced to the trimmer.

The machine to which my invention is applicable is designed to trim the top lifts that are usually put on wood or other style heels for shoes. Said machine is adapted to trim the top lift so as to give it the particular shape called for.

Only such parts of the machine are shown that my improvements cooperate with. The general construction and arrangement of such machines are not changed; therefore it was not thought necessary to show or describe those parts. One of the main improvements herein is that which allows the trimming head, with its various adjustments, to be moved concentrically about the trimmer axis, thus permitting any angle that may be desired by moving the head to the desired position. The other important adjustment is that of the platform, which is adjusted with the usual worm acting on a segmented gear (not shown) to give the platform the proper slant for the particular heel to be worked upon. The other minor adjustments carried by and operating therewith will be detailed further on.

Referring to Fig. 1, the head 10 of the trimming machine is illustrated. The main shaft 11 is housed in suitable bearings 12-13, having a drive pulley 14. The outer end of said shaft may be provided with a hand wheel or other means for turning the shaft 11. To the other or free end of said shaft is secured the trimmer or cutter 15, being of such size and shape as to perform the necessary work on the top lift 16, as it is presented thereto. The bearing 13 has an extended hub (not shown) on which is mounted the adjustable guard block and bracket 17, and held in proper working relation to the trimmer by reason

of the adjusting screw 18. The adjusting screw 19 adjusts the relation of the guard block arm 20 so that the guard and trimmer are always in proper relation to each other. 5 The knurled headed screw 21 regulates the position of the guard vertically with relation to the trimmer. The bifurcated guard arm 22 is hinged at its upper end to the arm 20 by a screw 23. 10 The lower part of the arm carries the curved guard 24 that houses the trimmer, the upper part thereof fitting the enlarged curved part of the arm 22, and is secured thereto by means of screws 25. Said guard may form a part of 15 a perfect sphere, except at its lowermost point 26, which is skived so as to allow the trimmer to get close to the heel. The guard 24 is held in operating position to the trimmer by reason of the spring 27, while the 20 screw 28 holds the same in proper position. Thus it will be seen that once the guard is adjusted to the trimmer, it operates always about the axis of the same, which is a decided advantage for any operation on the heel, be 25 it curved or straight. In addition to the above it not only serves as a guide for the work but protects the same, also the operator from contact with the cutter accidentally or otherwise.

Referring now to Fig. 2, it will be seen that 30 the platform 29 is provided with an adjustable guard plate 30, held in proper position with relation to the trimmer by screw 31, while to the side of said platform is another adjustable sliding plate 32, a knurled nut 33, giving the proper adjustment thereto. To the upper part of plate 32 is secured an adjustable trimming knife 34. The platform is so positioned as to rock on a radius from the cutting point of the trimmer, thus keeping 40 the trimmer and guard plate 30 always in relation to each other, irrespective of other adjustments that may have been made.

In the operation of the machine, each designed heel is provided with its proper size 45 top lift 16 that has to be shaped to that particular style heel. In Fig. 8, a portion of a heel is shown with the top lift 16 in position for the operator to place the same against the platform 29 and guard plate 30. He 50 moves the same upwardly till the guard 24 is reached, the trimmer starts cutting the outer edge to the shape of the heel, and then he turns the same around so as to trim the breast as well; by reason of the guard being 55 curved as shown, the operator is enabled to cause the lift to be entirely trimmed, as has been pointed out. After the edge trimmer has completed the edge, the lift is complete without the necessity of further cutting or 60 trimming. The lift is then ready for the burnisher to finish in the particular style. Here is where the decided advantage accrues, by reason of the operator being able to trim the whole top lift 16 by machine instead 65 of only partially, and requiring additional

manual labor before the same becomes a finished product.

Referring to Fig. 5, it will be seen that I mount upon the adjustable slide 32 a knife 35, which is held to said slide 32 by screw 36. 70 This not only gives an adjustment to the knife 35 to trim any lift, be it $\frac{1}{16}$ or $\frac{1}{4}$ inch thick, but the knife, by reason of its vertical adjustment and its angular adjustment, may be made to operate on any lift presented. 75 This applies to the curved as well as the straight breast heels. Again, by reason of its angular adjustment, it is adapted to give that slight bevel cut to the outer edge of the lift that is desired to complete the work on the lift. As the trimmer cuts the lift and as the operator turns the same around, the shaggy edge contacts with the knife 35, and is perfectly and completely trimmed.

It will be apparent with reference to Figs. 85 3 and 4, that it is a simple operation to trim the outer edges of the lift, it being only necessary to keep the same in contact with the guard and turning the same around as fast as the trimmer cuts. The trimmer under the 90 guard shown in Fig. 3 is adapted to trim any size top lift of any shape, while the trimmer under the guard shown in Fig. 4, which is given the same reference character only 95 primed, is adapted to trim the outer edge of any lift, and the straight breast of the heel, but is of no use on curved breasts. While this latter designed guard is superior to any known, for its work and the protection afforded, yet it can only operate on heels as described.

Referring to the modification shown in Fig. 105 7, it will be observed that the guard 24' is the same as that shown in Figs. 1, 2, 3 and 6, with only the exception that the same is cut away as at 37. This permits the operator to see at all times the operations being performed on the lift, viz, the trimming and the final operation by the knife 35 with all the other advantages.

As has been noted, the guard carrying bracket is adjustable about the axis of the trimmer, while the guard itself is adjustably secured thereon to be moved towards or from the trimmer, or may be raised or lowered with 110 respect thereto. While the platform is adapted to assume any desired angle, as noted, the angular movement at all times being on a radius from the cutting point of the trimmer. The feather edge knife 35 may or may not need additional adjustment for different styles. Having this keen-edge knife adjustable on the platform both up and down thereto, as well as being able to adjust its inclination to perform its particular class of work, is 115 of a material advantage.

All trimmers known at present are inadequate for finishing a heel of any description without making alterations in the adjustments or in substituting parts to finish a par- 120 125

ticular heel, to meet the necessary specifications. Means have been provided for holding the heel in a position while a trimmer has taken off the outer edge or on straight breast of heels; but in this device it is necessary for the operator to either trim the fringe himself or to pass that to another, which consumes time and labor. In another heel trimming machine there is a disk guard that is 10 suitably mounted on a slide having a vertical adjustment, said slide being adjustable in either direction to or away from the top lift, according to the thickness. In the operation of this machine, a curved breast cannot be 15 accomplished thereon without additional manual labor.

While I have herein described the form of my invention as at present preferred and which I consider to represent the best embodiment thereof, yet I desire to have it understood that the various forms shown are only illustrative and that the invention may be carried out in other ways than that shown and described; for instance, the arrangement 20 of the guard may be cut out on each side of a central guard covering the trimmer and leaving its lower edges with the curve, as shown, or the curved lower part of the guard may have only short extending arms on each side 25 of the central guard section, as may be desired, or the curved guard may be provided with its lower edges curved, more or less extended. Any of the forms may be used or any modifications thereof to advantage, and they 30 are all intended to come within the scope of the claims.

What I claim as new and desire to secure by Letters Patent is:

1. In a top lift trimming machine, a trimmer, a head mounted to move concentrically about the same, an adjustable arm extending from said head, means for mounting a curved guard thereon, means for adjusting the guard toward or away from the trimmer, a platform having an adjustable guard plate to cooperate with the trimmer, and an adjustable slide carrying a trimming knife to finish the trimming of the lift.

2. In a top lift trimming machine, comprising a trimmer, a head mounted to move concentrically about the same, an arm extending outwardly from said head to support a curved guard thereon, means for adjusting the same up and down with relation to the trimmer, an adjustable platform, an adjustable guard plate, and an adjustable slide carrying an adjustable blade for finishing the trimming operation on the lift.

3. In a top lift trimming machine, comprising a head adjustable on the axis of the trimmer, an adjustable arm extending outwardly from said head, a curved guard secured to said arm, means for moving the same toward or away from the trimmer, an adjustable platform having a guard plate and

a movable slide, and a knife adjusted to the top of the slide whereby the lift is trimmed and completely finished.

4. In a top lift trimming mechanism for heels, of a revolving trimmer, a head mounted thereon to move concentric therewith, a curved guard carried by said head, said guard adapted to cooperate with the trimmer whereby the inner and outer parts of said lift is completely trimmed in one operation, a movable platform carrying an adjustable guard plate and an adjustable slide, and a knife adjusted to the top of the slide, whereby the lift is trimmed and completely finished. 70

5. In a top lift trimming mechanism for heels, comprising a trimmer, means for supporting and carrying a partially spherical guard therefor, said guard having its lower edge skived, means for holding said guard in proper relation to said trimmer, means for swinging said guard free from said trimmer without effecting the several adjustments, a platform movable on a radius of the point of said trimmer, a guard plate and slide both adjustably mounted thereon, and an adjustable knife disposed at an angle on said slide, whereby the edge of the heel is further trimmed of any roughness that may be left thereon. 85

6. In a top lift trimming mechanism for heels, comprising a revolving trimmer, movable means for supporting and carrying a partially spherical guard, said guard remaining in axial relation to said trimmer, means for adjusting said guard in any direction thereto and adapted for separate movement without affecting said adjustments, a platform movable on a radius of the point of said trimmer, a guard plate to cooperate with said trimmer for holding said lift in proper relation to said spherical guard, and a vertically adjustable slide carrying a knife adjusted to remove any roughness and give a slight bevel to the lift. 95

7. In a top lift trimming mechanism for heels, a revolving cutter, a movable means for supporting and carrying a partially spherical guard, said cutter revolving thereunder, said guard adapted to be adjusted up or down, in or out with respect to said trimmer, and adapted for swinging said guard free from said trimmer without affecting the adjustments, a platform movable on a radius with the cutting point of said trimmer, a guard plate for the work whereby the latter is held against said spherical guard, while said trimmer trims the outer sides of the lift and the curved breast thereof, and a movable positioned knife for beveling the lift. 110

8. In a top lift trimming machine, a trimmer, a head mounted to move concentrically therewith, having an arm extending therefrom, said arm having an enlarged end to which a guard is attached, the face of said enlarged end being curved to correspond with 120

the portion of a sphere having its center coincident with the axis of the trimmer, means for adjusting said guard with relation to said trimmer, a platform having a guard plate to cooperate with said trimmer, and means co-operating with said trimmer and guard plate to completely trim the lift.

9. In a top lift trimming machine, a trimmer, a head mounted to move concentrically thereto, an arm carried by said head provided with a guard having curvature corresponding to a chord having its center coincident with the axis of rotation of the trimmer, and partially enclosing the trimmer to protect the work and the operator, means for adjusting the guard with relation to the trimmer, an adjustable platform, an adjustable guard plate carried thereby, an adjustable slide, and a knife adjusted to the top of the slide whereby the lift is completely trimmed and finished.

10. In a top lift trimming machine, a revolving trimmer, a head mounted thereon to move concentrically therewith, a guard, a supporting member to which the guard is attached, said guard having a curved body portion and a skived lower edge serving as a gauge to determine the extent of the cut to be made by the trimmer on the top lift, a movable platform carrying an adjustable guard plate and an adjustable slide, and a knife adjusted to said slide, whereby the lift is trimmed and completely finished.

In testimony whereof I affix my signature.
FREDERICK H. HUMMEL.
